DESIGN FOR A BUTTON

Henry Lorber, New York, N. Y.

Application March 18, 1940, Serial No. 91,017

Term of patent 7 years

To all whom it may concern:

Be it known that I, Henry Lorber, a citizen of the United States and resident of New York city, in the county of New York and State of New York, have invented a new, original, and ornamental Design for a Button, of which the following is a specification, reference being had to the accompanying drawing, forming a part thereof,

Fig. 1 is a top plan view of a button, showing my new design.

Fig. 2 is a side elevational view of the same.

Fig. 3 is a transverse sectional view taken on the line 3—3 of Fig. 1.

I claim:

The ornamental design for a button, as shown.

HENRY LORBER.
